UNITED STATES PATENT OFFICE.

HUGH A. JACOBS AND CHARLES E. JACOBS, OF MINNEAPOLIS, MINNESOTA.

MULTIPLE-NEEDLE HEMSTITCHING MECHANISM.

Application filed November 24, 1920. Serial No. 426,260.

To all whom it may concern:

Be it known that we, HUGH A. JACOBS and CHARLES E. JACOBS, citizens of the United States, residing at Minneapolis, in the county 5 of Hennepin and State of Minnesota, have invented certain new and useful Improvements in Multiple-Needle Hemstitching Mechanism; and we do hereby declare the following to be a full, clear, and exact description of the invention, such as will enable others skilled in the art to which it 10 pertains to make and use the same.

Our invention has for its object to provide an extremely simple and highly efficient hemstitching attachment or mechanism for sewing machines and more particularly for sewing machines of the rotary shuttle or rotary hook type.

Hitherto, hemstitching of special character has been done by expensive sewing machine mechanism, which, because of the expense was not adapted for domestic use. Our hemstitching attachment or device is adapted to be applied either at the factory 25 or upon machines already in use at comparatively small cost, and, at the same time, will be highly efficient for the purposes had in view.

In the preferred embodiment of the invention, there is a plurality of needles and rotary shuttle or hook. The two needles are carried by a common head and are associated with a piercer, the function of which is to enlarge and properly shape holes previously made by one of the needles. The two needles are arranged to throw interlapping thread loops, that is, the thread loop from each needle will be thrown laterally toward the other needle, so that, in a direction transversely of the feed movement, there will be a lapping or interlapping of these thread loops, the one beyond the other. The rotary hook is arranged to pass through these two thread loops from the two needles 40 and to carry the same around the third thread that comes from the shuttle, thereby forming a three-thread stitch in which two outside threads, supplied from the two needles, will be interlocked with and connected 45 by said third thread that comes from the shuttle or bobbin.

The preferred embodiment of the invention is illustrated in the accompanying drawings, wherein like characters indicate like 50 parts throughout the several views.

Referring to the drawings:

Fig. 1 is a side elevation showing a sewing machine of the rotary shuttle type having our attachment or hemstitching device applied thereto; 60

Fig. 2 is a front elevation of the machine shown in Fig. 1;

Fig. 3 is a view partly in side elevation, but with some parts sectioned on the line 3—3 of Fig. 2; 65

Fig. 4 is a fragmentary plan view showing the needle plate and certain associated parts;

Fig. 5 is a perspective showing the needles, piercer, presser foot, needle plate and feed teeth of the machine; 70

Fig. 6 is a view partly in front elevation but with some parts sectioned on the irregular line 6—6 of Fig. 3;

Fig. 7 is a view corresponding to Fig. 3, but with the shuttle and hook in full elevation; 75

Fig. 8 is a horizontal section taken on the line 8—8 of Fig. 6;

Fig. 9 is a plan view illustrating the hemstitching structure; and 80

Fig. 10 is an enlarged view showing the manner in which the three threads are interlocked to form the stitch.

Of the parts of the sewing machine, it is desirable, for the purposes of this case, only 85 to particularly note the bed plate 11, the head arm 12, the face plate 13, the needle bar 14, the presser foot bar 15, the presser foot 16, the thread take-up arm 17, the thread tension device 18, the main driving shaft 19, 90 the shuttle driving forked or two-pronged pinion 20 and the rotary shuttle 21, all of which parts are of well known construction and operate in a manner well understood by those familiar with this art. This rotary shuttle 21, as is customary, is set to rotate on an oblique axis within the customary shuttle race 22, and said shuttle has diametrically opposite seats 23 with which the prongs of the driving fork or pinion 20 engage through the lower half rotation. The shuttle 21 contains the customary bobbin and bobbin case 24, and the bobbin case has the customary cover 25, which latter noted parts also operate in a well known manner. Moreover, the rotary shuttle 21 has a peripheral hook 21^a, which, in this instance, is made very thin or narrow and is arranged to pass between the two needles presently to be described. 100

Below the presser foot 16, the needle plate 17 is shown as provided with a raised portion 17^a that is formed with two perforations 26 and 27, and the presser foot 16, as shown, is provided with perforations 28 and 29 that overlie, respectively, said perforations 26 and 27. The numeral 30 indicates the feed teeth that work through the needle plate in the usual way.

As already indicated, our invention contemplates the use of a plurality of needles, and preferably also, a co-operating piercer. These two needles 31 and 32 and the piercer 33 are all preferably rigidly secured to and depend from a common head 34 having a shank 35 adapted to be secured to the lower end of the needle bar 14 by the customary clamping head 14^a.

The piercer 33 is located directly behind the needle 31 and is so spaced therefrom that it will always come into a needle hole just back of the hole occupied and, in fact, primarily made by said needle 31. The function of this piercer 33 is to enlarge and to better form the hole in the cloth and, hence, said piercer, at least in its upper portion, would preferably be approximately rectangular in cross section, inasmuch as that is the form of hole ultimately desired in hem-stitching.

The two needles 31 and 32 are passed through the holes 28 and 26 of the presser foot 16 and needle plate, respectively, while the piercer 33 is passed through the holes 29 and 27. Threads *a* and *b* are supplied respectively to the needles 31 and 32. These threads, as shown, are supplied from spools 36 and 37 mounted on the head arm 12 and said two threads are passed through suitable guides 38, through the tension device 18, through the slack take-up arm 17 and through suitable guides 39 in the needle bar clamp 14^a.

The lower or third thread carried by the bobbin 24 is indicated by the character *c*, that is manipulated in substantially the customary way under rotation of the shuttle; but in this arrangement, the hook of the shuttle passes through the interlapped loops of the spool threads *a* and *b*, and, hence, both of the threads *a* and *b* are turned about said lower thread *c* and the three threads become interlocked, as best shown in Fig. 10. Here it will be noted that the lock or third thread *c* is alternately interlocked with the threads *a* and *b*. Preferably, the thread *a* is fed under greater tension than the thread *b*, so that when the thread *c* is drawn taut, the thread *b* will be pulled laterally toward the thread *a*. The thread *b* will be stitched in the body of the cloth *y*, see particularly Fig. 9, while the thread *a* will be stitched into the holes *y*¹, which are made as a part of the hemstitching and are finally formed

by the piercer 33. This manner of stitching 65 reinforces and gives good form to the perforations *y*¹. For single hemstitching, it is necessary only to stitch along one side, but for double hemstitching, the stitching operation must be repeated on both sides. For 70 example, in Fig. 9, single hemstitching at the right is shown as completed, but double hemstitching at the right and left is not fully completed in said view, Fig. 9.

Obviously, very high grade hemstitching 75 may be done by this attachment, especially when the stitching operation is repeated on both sides of the row of perforations. The manner of forming the stitches in the perforations and in the body of the cloth along 80 the line of perforations and of drawing the threads in the stitching operation, not only definitely forms the hemstitch but provides a hemstitch that will keep its form after it has been made.

The fact that the needles are all on a common head is highly important because they can be made in exact proper adjustment and cannot thereafter get out of adjustment, and, moreover, may be handled as a single 90 unit.

What we claim is:

1. In a sewing machine, the combination with two needles adjacently connected for simultaneous movements, a shuttle mechanism including a hook-acting member arranged to pass between said needles and through overlapped thread loops projected from the several needles and to carry said thread loops around the thread from the shuttle mechanism, and a piercer movable with said needles, one of said needles and said piercer being spaced in the line of the feed movement, and one thereof being arranged to enter holes formed by the other. 95

2. In a sewing machine, the combination with two needles adjacently connected for simultaneous movements, shuttle mechanism including a rotary hook arranged to pass between the said needles and through overlapped thread loops projected from the several needles and to carry said thread loops around the thread from the shuttle, and a piercer movable into the holes formed by one of the needles and serving to enlarge and 100 complete the formation of the holes. 105

3. Two sewing machine needles and a piercer connected to a common head and having a common stem, said piercer being located directly beyond one of said needles and positioned so that it will enter holes primarily formed by said needle located in front thereof. 115

In testimony whereof they affix their signatures.

HUGH A. JACOBS.
CHARLES E. JACOBS.
